JULES PFLIMLIN, OF MULHOUSE, FRANCE

SPINNING FRAME AND THE LIKE

Application filed January 6, 1930. Serial No. 418,713.

My invention relates to sliver or roving drawing devices devised for the drawing effected by spinning frames and the like, as also by preparatory machines and for drawing frames and more particularly to an improvement in weighting the drawing rolls of such mechanisms.

In my co-pending application Serial No. 418,711 filed of even date herewith I have described and claimed a novel middle top roll so soft and compressible that when pressed against the middle bottom roll its sleeve is deformed in a manner to engage said bottom roll over a considerable length of its circumferential surface. I have discovered that middle top rolls of the type just described are most effective when saddle-weighted or are weighted by a floating weighting-roll and my invention will be described in connection with such middle top rolls although its application in this art is not limited thereto.

The nature of my invention will be understood from the following description of the accompanying drawings, in which:

Figure 1 is a cross-sectional view of a spinning frame showing my improved weighting of middle top rolls;

Fig. 2 is a plan view of the spinning frame of Fig. 1, with the front and back top rolls removed and the weighting roll broken to expose one middle top roll which is shown in section; and

Fig. 3 is a view, in perspective, of one of the supports for the weighting roll.

In the embodiment of the invention illustrated in the drawings the spinning frame is shown as of a usual type comprising co-acting front rolls 2-4, co-acting back rolls 6-8 and co-acting middle rolls 10-12 each top roll being mounted for rolling contact with its co-acting bottom roll and the middle pair being located in the frame in spaced relation to the front and back pairs. All the top rolls, as illustrated, are floaters, i. e. they are driven only by contact with the positively driven bottom rolls, and consequently are shown as seated loosely in bearing slots formed in the cap bars 14. As is customary the assembly of rolls is held in the frame in a position oblique to the hori-

zontal, the bars 14 being inclined upwardly from front to rear.

Secured to the bars 14, one at each end of the middle top roll (Fig. 2) are supports 16 for holding a weighting roll 18 in position above the middle top roll 10. Each support 16 is L-shaped, see Fig. 3, the base 20 being slotted to be adjustable under a holding screw 21 and the upstanding leg 22 being widened to receive against it the shaft ends 60 of two weighting rolls on adjacent frames. When secured to the cap bar the leg 22 stands perpendicular thereto and, hence inclined to the vertical. The adjustment on the screw 21 is made to place the leg with its face in a plane parallel to the axis of the top roll 10 and sufficiently forward of said axis to set the weighting roll above said top roll. The shaft ends 24 of the weighting roll bear against the inclined legs 22 of the supports 70 which hold the weighting roll in floating contact with the middle top roll.

The preferred construction of middle top rolls to be thus weighted is shown in Fig. 2. The collars 26 of the arbor are bridged 75 by a skin covered, elastic sleeve 28 forming an annular air chamber between the sleeve and the arbor shaft 30. This type of roll is so soft that, under pressure, it is deformed from end to end to conform to the curvature 80 of the middle bottom roll and obtain a belt like grip on the passing sliver all as described in my co-pending application referred to. This type of middle top roll will also be deformed by the weighting roll 18 as shown by 85 Fig. 1. Notwithstanding this double deformation of the elastic middle top roll it rolls easily on the middle bottom roll with a progressive circumferential deformation. When power is applied to the machinery all three 90 rolls, bottom, top and weighting, start their rotation at the same instant and additional, injurious draft on the sliver, due to a dragging top roll, is never present. The grip on the bottom roll and weighting roll obtained 95 by the deformed top roll is such that rotation of all three is initiated simultaneously.

I preferably, but not necessarily, provide the weighting roll 18 with a sheath or covering 100 32 of some tenacious material, conven-

iently tubular knitted fabric of a size to fit snugly on the body of the roll. This covering will gather and remove all fly and small portions of fibre from the surface of the middle top roll 10 thus keeping it clean and enabling it continually to grip the sliver with its smooth leather skin. Whenever the weighting roll has accumulated a considerable amount of waste on its fabric cover, the cover is easily stripped off and replaced.

10 10 The nature and scope of my invention having been indicated, and its preferred embodiment having been specifically described, what is claimed as new is:—

15 1. In a spinning frame or the like, co-acting front rolls, co-acting back rolls, co-acting middle rolls including a middle top roll having a covering sleeve that is very soft and readily deformable at its under engaging surface when pressed against the co-acting middle bottom roll enabling it to engage said bottom roll over a considerable circumferential arc thereof, and a weighting roll mounted to rest upon and so to deform said middle top 25 roll at the same time deforming its upper surface to engage said weighting roll over a considerable circumferential arc thereof.

20 2. In a spinning frame or the like, co-acting front rolls, co-acting back rolls, co-acting middle rolls including a highly resilient middle top roll, and a weighting roll applying sufficient pressure to said middle top roll to create lengthwise depressions both at its top and at its bottom while engaged between said 25 two rolls.

25 3. A spinning frame or the like comprising cap bars, front, middle and back pairs of drawing rolls supported by said cap bars, said middle pair being spaced from both 30 front and back pairs and the middle top roll being deformable and floating on its co-acting bottom roll, and a weighting roll arranged to float on and apply sufficient pressure to said middle top roll to deform it.

40 45 In testimony whereof I affix my signature.
JULES PFLIMLIN.
